UNITED STATES PATENT OFFICE

LEONIDAS L. LANDIS AND EARL G. SAUER, OF LIMA, OHIO

DESIGN FOR A CHRISTMAS TREE HOLDER

Application filed October 5, 1931. Serial No. 41,309. Term of patent 3½ years.

To all whom it may concern:

Be it known that we, LEONIDAS L. LANDIS and EARL G. SAUER, citizens of the United States, residing in the city of Lima, in the county of Allen and State of Ohio, have invented a new, original, and ornamental Design for a Christmas Tree Holder, of which the following is a specification, reference being had to the accompanying drawing, forming part thereof.

We claim:

The ornamental design for a Christmas tree holder, as shown.

LEONIDAS L. LANDIS.
EARL G. SAUER.
